(57) **CLAIM**

The ornamental design for a rear bumper for a vehicle, as shown and described.

DESCRIPTION

FIG. 1 is a perspective view of a rear bumper for a vehicle showing our new design in a first embodiment.

FIG. 2 is a right side elevation view thereof.

FIG. 3 is a left side elevation view thereof.

FIG. 4 is a front elevation view thereof.

FIG. 5 is a rear elevation view thereof.

FIG. 6 is a top plan view thereof.

FIG. 7 is a bottom plan view thereof.

FIG. 8 is a perspective view of a rear bumper for a vehicle showing our new design in a second embodiment.

FIG. 9 is a right side elevation view thereof.

FIG. 10 is a left side elevation view thereof.

FIG. 11 is a front elevation view thereof.

FIG. 12 is a rear elevation view thereof.

FIG. 13 is a top plan view thereof; and,

FIG. 14 is a bottom plan view thereof.

The broken lines illustrate portions of the rear bumper for a vehicle that form no part of the claimed design.
